UNITED STATES PATENT OFFICE.

JESSE E. S. RUSSELL, OF LOS ANGELES, CALIFORNIA.

CARRIER FOR LAUNDRY.

Application filed May 17, 1927. Serial No. 191,963.

This invention relates to a laundry carrier and it is an object of the invention to provide a laundry carrier useful and effective in handling bundles or parcels of laundry, or 5 the like.

Many laundries employ systems under which the clothes are handled in bags or bundles. The clothes belonging to one customer are placed in bags, each carrying a 10 tag bearing an identifying number or mark. Bags containing the clothes of several customers are washed in a lot, after which the bags are sorted by means of the tags. One popular method of sorting is to apply the 15 bags to hooks, which hooks are numbered corresponding to the numbers on the tags attached to the bags and are key shaped to receive only the proper tags.

It is an object of this invention to provide 20 a laundry carrier useful in sorting or handling bags or bundles of laundry.

It is a general object of this invention to provide a laundry carrier of the type mentioned which is simple and convenient to 25 operate.

A further object of this invention is to provide a laundry carrier which occupies a minimum amount of space.

It is a further object of this invention to provide 30 a laundry carrier of the type mentioned embodying a novel and effective track construction.

It is a further object of this invention to provide various improved features of construction for a laundry carrier of the type 35 mentioned.

The various objects and features of the invention will be best and more fully understood from the following detailed description 40 of a typical form and application of the invention, throughout which description reference is had to the accompanying drawings, in which:

Fig. 1 is a side elevation of the apparatus 45 provided by this invention;

Fig. 2 is a plan view of the apparatus, being a view taken as indicated by line 2—2 on Fig. 1;

Fig. 3 is an enlarged view, taken as indicated by line 3—3 on Fig. 2;

Fig. 4 is an enlarged view, taken as indicated by line 4—4 on Fig. 2;

Fig. 5 is an enlarged view, taken as indicated by line 5—5 on Fig. 1; and

Fig. 6 is an enlarged view, taken as indicated by line 6—6 on Fig. 2.

My invention provides, generally, a plurality of carriers 10, pins or other like projections 11 detachably mounted on the carriers, a pair of delivery rails 12 for carrying the carriers between two positions such as the positions A and B indicated in Fig. 1 of the drawings, a pair of return rails 13 for returning the carriers from one of said positions to the other position, means 14 for transferring the carriers between one end 60 of the pair of rails 12 to the corresponding end of the return rails 13, means 15 for transferring the carriers from the return rails 13 to the delivery rails 12, and supporting means or standards 16 for the rail structures. 70

Each carrier 10 includes an elongated body or beam 17 provided at its ends with heads 18, each carrying a pair of wheels 19. The 75 heads 18 extend transversely in a horizontal direction at the ends of the beam and the wheels 19 are mounted in spaced relation on the heads to effectively support the beam so that it does not tilt or turn when loaded 80 or in operation. The wheels 19 may be mounted on the head in any suitable manner, for instance, through suitable shafts carried in bearings 20 provided in the heads 19. In practice, I prefer to mount the shafts 85 in ball or roller bearings so that the carrier operates easily. One of the wheels 19 at one end of the carrier is connected to operate with the corresponding wheel at the other end of the carrier. In practice, the 90 wheels, which are to operate together, may be connected through a common shaft 22 extending between the ends of the carrier parallel with the beam 17. The wheels may be keyed on the shaft 22 to turn with the 95 shaft. By thus connecting the wheels with the shaft to turn together, the carrier will operate on the rails without binding. In the construction illustrated in the drawings, the heads 18 provided at the ends of the 100 beam are in the form of castings. The wheels 19 are preferably flanged so that they will remain on the rails during the operation of the device, as hereinafter described. In practice, bumpers 23 may be provided on the back of the body of the carriers to act as spacers for the carriers in the event that they are brought together. 105

The pins 11, which may be made suitable for carrying bags of laundry, or the like, 110 are, in accordance with this invention, detachably mounted on the front of the carrier

beam 17. In the construction shown in the drawings, each pin is carried on a plate 25 having openings to receive mounting screws 26 projecting from the beam 17. The openings are provided in the plate 25 so that the plate can be applied to and removed from the screws at will and is effectively held on the beam when in position on the screws, as shown in Fig. 6 of the drawings. The pin 10 may be key-shaped, or otherwise made to receive only certain tags on the laundry bags in order to carry out the system of sorting above referred to.

The delivery rails 12 are preferably straight, horizontally disposed rails made sufficiently long to carry the carriers between the desired positions A and B. It will be obvious that the rails 12 may be of any desired length and, if necessary, may be curved to bring the carriers to the desired positions at A and B. It is to be understood, of course, that the rails 12 are spaced apart to properly receive the wheels of the carriers. Stops 30 are provided at the ends 25 of the rails to limit the movement of the carriers.

The return rails 12 may correspond, generally, to the delivery rails except that they are mounted in a different horizontal plane 30 and may be shorter. In the arrangement shown, the return rails are mounted in a horizontal plane above the rails 12, the space between the rails 12 and 13 being just sufficient to properly accommodate the carriers 35 in their operation along the rails 12.

In the preferred construction, the rails are supported by means of the standards 16. The standards are preferably arranged at the ends of the rails and are provided with 40 inwardly extending brackets 28 on which the rails rest. In the preferred construction, diagonal braces 29 are provided at opposite sides of the standards to engage under the rails 12 at points spaced from the standards 45 and thus brace and support the rails 12 between and beyond the standards. With this construction, the rails 12 may be of considerable length without requiring standards intermediate the ones supporting the end portions 50 of the rails.

The means 14 provided for transferring the carriers from the delivery rails 12 to the return rails 13 includes, generally, movable rail extensions 31 at the ends of the return rails 13. The movable rail extensions 31 are pivotally mounted adjacent the ends of the rails 13 and project outwardly or beyond the ends of the rails 13 to engage the rails 12 at points suitably spaced inward of their outer ends, as illustrated in Figs. 1 and 3 of the drawings. The rail extensions 31 preferably engage the rails 12 so that the rails 12 will carry at least one carrier 10 outward of or beyond the ends of the extensions. The extensions 31 are carried by pivot pins

35 so that their outer portions will lift or swing upwardly as the carriers are moved outwardly on the end portions of the rails 12. As a carrier is moved to the ends of the rails 12, the extensions 31 are automatically 70 lifted by contact with the carrier, and when the carrier has passed the outer ends of the extensions 31, the extensions 31 drop back to their normal position, as shown in Fig. 1. When the extensions 31 have thus dropped 75 back into engagement with the rails 12, the carrier may be operated over the extension 31 onto the rails 13. The outer ends 36 of the extensions 31 are preferably beveled or finished to seat on the rails 12, as shown 80 throughout the drawings, and, in practice, spaced projections 37 are provided on the outer ends of the extensions 31 to straddle the rails 12 and thus guide the extensions 31 into proper position with reference to the 85 rails.

The means 15 at the opposite ends of the rails 12 and 13 for transferring the carriers from the rails 13 to the rails 12 includes movable rail extensions 51 projecting from the ends of the rails 13. The rail extensions 51 correspond, generally, to the rail extensions 31 and are pivotally mounted adjacent the ends of the rails 13 on pivot pins 35^a. In the preferred form of the invention, the rail 95 extensions 51 may be provided with means for normally yieldingly holding them up or away from the rails 12, as shown in the drawings. This means may include a weight or spring construction. In the draw- 100 ings, I have shown a spring 60 in connection with each rail extension 51 normally yieldingly holding it up, as clearly shown in Figs. 1 and 4. When a carrier is moved from the rails 13 onto the extensions 51, the extensions are depressed into engagement with the rails 12, allowing the carrier to move down the extensions 51 onto the end portions of the rails 12. When the carrier reaches the rails 12, it passes off of the extensions 105 51, allowing them to return to the upper position.

In operating the device, any suitable number of carriers may be provided in the apparatus, the number depending upon the size 115 of the apparatus and the work to be handled thereby. As a typical manner of using the apparatus, we will consider a carrier arranged in the position indicated at A in Fig. 1. While in this position, the desired pins 11 are mounted on the carrier and bundles of laundry, or the like, are sorted onto the pins 11. When the carrier is loaded, it is moved along the tracks 12 to the unloading position B, at which point the bundles of laundry are 125 removed after which the pins 11 may be removed. As the carrier is moved away from the loading position A, another carrier may be moved into the loading position and may be loaded while the carrier first loaded is in 130

the position B being unloaded. When the carrier has been unloaded at B, it may be transferred to the return rails 13 through the means 14, and, when again desired for use, may be transferred from the rails 13 back to the rails 12 by the transferring means 15. It is to be noted that the carriers are moved only a comparatively short distance vertically, thus minimizing the work necessary in transferring the carriers between the rails. Further, it is to be noted that the carriers are transferred between the rails without the manual manipulation of switches, or like devices. As the carriers are moved through the means 14, the rail extensions 31 are automatically lifted by the wheels of the carrier. In moving a carrier through the means 15, the rail extensions 51 are depressed by the weight of the carrier, making manual operation unnecessary. It is to be understood that the apparatus can be designed and proportioned so that two or more carriers can be arranged on the end portions of the rails 12 beyond the transferring means, and that the apparatus can be operated in any desired manner to suit individual needs.

Having described only a typical preferred form of my invention, I do not wish to limit myself to the specific details set forth, but wish to reserve to myself any changes or variations that may appear to those skilled in the art or fall within the scope of the following claims.

35 Having described my invention, I claim:

1. Apparatus of the character described including a carrier, two sets of rails for the carrier one located above the other, and means for transferring the carrier between the ends of the sets of rails including pivotally mounted rail extensions.

2. Apparatus of the character described including a carrier, delivery rails for the carrier, return rails for the carrier located above the delivery rails, and movable rail extensions at the ends of the return rails for transferring the carriers between the rails.

3. Apparatus of the character described including a carrier, delivery rails for the carrier, return rails for the carrier located above the delivery rails, movable rail extensions at the ends of the return rails for transferring the carriers between the rails, and means in connection with the extensions at one end of the return rails normally yieldingly holding said extensions away from the delivery rails.

4. Apparatus of the character described including a carrier, delivery rails for the carrier, return rails for the carrier located above the delivery rails, movable rail extensions at the ends of the return rails for transferring the carriers between the rails, and springs in connection with the extensions at one end of the return rails normally yieldingly holding said extensions away from the delivery rails.

5. Apparatus of the character described including a carrier, delivery rails for the carrier, return rails for the carrier located above the delivery rails, pivotally mounted rail extensions at the ends of the return rails for transferring the carriers between the rails, and springs in connection with the extensions at one end of the return rails normally yieldingly holding said extensions away from the delivery rails.

6. Apparatus of the character described including a carrier, two sets of rails for the carrier one located above the other, and means for transferring the carrier between the ends of the sets of rails including pivotally mounted rail extensions having spaced projections at their outer ends.

7. Apparatus of the character described including a carrier, a pair of return rails for the carrier, a pair of delivery rails for the carrier arranged below the return rails and projecting beyond the ends of the return rails, and movable rail extensions on the ends of the return rails projecting to the end portions of the delivery rails.

8. Apparatus of the character described including a carrier, a pair of return rails for the carrier, a pair of delivery rails for the carrier arranged below the return rails and projecting beyond the ends of the return rails, and movable rail extensions pivotally mounted at the ends of the return rails for transferring the carrier between the rails.

9. Apparatus of the character described including a carrier, a pair of return rails for the carrier, a pair of delivery rails for the carrier arranged below the return rails and projecting beyond the ends of the return rails, stops at the ends of the delivery rails, and movable rail extensions on the ends of the return rails projecting to the end portions of the delivery rails.

10. Apparatus of the character described including a carrier, a pair of return rails for the carrier, a pair of delivery rails for the carrier arranged below the return rails and projecting beyond the ends of the return rails, and movable rail extensions pivotally mounted at the ends of the return rails for transferring the carrier between the rails, the extensions having spaced projections at their outer ends to straddle the delivery rails.

11. Apparatus of the character described including a carrier, a pair of return rails for the carrier, a pair of delivery rails for the carrier arranged below the return rails and projecting beyond the ends of the return rails, rail extensions pivotally mounted at the ends of the pair of return rails for transferring the carrier between the two pairs of rails, and means in connection with the extensions at one end of the pair of return rails normally yieldingly holding them up away from the delivery rails.

12. Apparatus of the character described

including a carrier, a pair of return rails for the carrier, a pair of delivery rails for the carrier arranged below the return rails and projecting beyond the ends of the return rails, rail extensions pivotally mounted at the ends of the pair of return rails for transferring the carrier between the two pairs of rails, and springs in connection with the extensions at one end of the pair of return rails normally yieldingly holding them up away from the delivery rails.

13. A laundry carrier including a track, a beam carried by the track, a plurality of pins, and means detachably mounting the pins on the beam, said means including plates carrying the pins and projections on the beam for releasably holding the plates. 15

In witness that I claim the foregoing I have hereunto subscribed my name this 3rd day of May, 1927.

JESSE E. S. RUSSELL.
